AIR CONDITIONER

John F. Halbeisen, Detroit, Mich.

Application March 25, 1954, Serial No. 29,687

Term of patent 14 years

(Cl. D62—4)

—1.

—2.

To all whom it may concern:

Be it known that I, John F. Halbeisen, a citizen of the United States, residing in the city of Detroit, county of Wayne, and State of Michigan, have invented a new, original, and ornamental Design for an Air Conditioner, of which the following is a specification, reference being had to the accompanying drawings, forming part thereof, in which:

Fig. 1 is a perspective view of an air conditioner embodying my new design;

Fig. 2 is a front elevational view of an air conditioner showing my new design;

Fig. 3 is a side elevational view thereof taken from the left side of Fig. 2;

Fig. 4 is a side elevational view taken from the right side of Fig. 2; and

Fig. 5 is a rear elevational view.

I claim:

The ornamental design for an air conditioner, substantially as shown.
